UNITED STATES PATENT OFFICE.

EMMA M. CLEVENGER, OF MUNCIE, INDIANA.

WINDOW CONSTRUCTION.

1,014,638.

Specification of Letters Patent. Patented Jan. 16, 1912.

Application filed February 21, 1911. Serial No. 610,082.

To all whom it may concern:

Be it known that I, EMMA M. CLEVENGER, a citizen of the United States, residing at Muncie, in the county of Delaware and State 5 of Indiana, have invented certain new and useful Improvements in Window Construction, of which the following is a specification.

This invention relates to improvements in 10 window construction.

The necessity and importance of providing means at windows for ventilating the room have long been recognized. Many different devices have been developed for the 15 purpose of permitting a flow of air through the window without having to open or shift the sash frames, but I am not aware that as yet any device so brought out has proven sufficiently practicable to be adopted by 20 architects and builders, and employed successfully in ordinary building construction.

The objects of my invention are to provide such improvements in window construction, that ventilation for living rooms, 25 public assembly halls, hospitals, and the like, may be facilitated. To do this I provide a member to constitute the bottom bar of the upper sash that is capable of permitting the 30 passage of air therethrough, and my invention accordingly consists of a sash bar having an opening therein, a lid to close the opening and fastening means whereby the lid is capable of being easily opened and also it may be locked securely; and at the 35 same time the device will not affect the construction or hinder the regular use and function of either of the sash frames constituting the window.

My invention is described in the following 40 specification, defined in the appended claims and illustrated in the accompanying drawings.

The several parts of the device as shown 45 in the different views are designated by similar characters of reference.

In the drawings, Figure 1 is a perspective view of a portion of a window, that is equipped with my invention. Fig. 2 is a plan view, and Fig. 3 is a front view, and 50 Fig. 4 is an end view of the sash bar. Fig. 5 is an enlarged transverse sectional view taken on the line 5—5 in Fig. 2. Fig. 6 is a front view, and Fig. 7 is a plan view enlarged showing the locking devices for the 55 lids F. Fig. 8 is a plan view of the sash bar

and lids F, the locking device having been removed.

In perfecting my present invention, the dominating idea has been to make the same practicable in every respect and capable of 60 use in windows of standard construction and consisting of ordinary double sash structure as shown in Fig. 1.

The objects of the invention are accompanied by the improved form and structure 65 of sash bar and lid and the fastening means therefor shown in the drawing. The sash bar is made of metal, preferably aluminum, and has the general structure shown in the drawings.

Formed integral with the flat body portion A is a rib A¹ which serves to stiffen the bar at its rear side and which also constitutes a sufficient bulk of metal, that the groove A² will not weaken the body portion. 75 This groove extends the full distance between the upright bars B of the sash and will receive the bottom edge of the glass C when the sash is glazed. Rising from the ends of the bar are the tongues A³ which 80 have suitable holes A⁴. To connect the sash bar securely to the upright bars B and to thereby complete the sash frame, the tongues A³ are inserted into suitable recesses provided therefor in the bottom ends of the upright sash bars B and are then made fast by dowels or bolts D. The vertical apron A⁵ which constitutes the front of the sash bar is of proper depth to constitute in the usual way a closure of the space between the 90 upper and lower sashes. The offsets A⁶ afford clearance for the strip (not shown) that forms a part of the standard window casing.

The utility of a sash bar constructed as 95 above described is obvious, it will not decay, weaken or sag, nor will it become loose at its connections, it renders practicable the providing of openings for the window whereby air currents may be passed through 100 the window without the necessity of moving either of the sashes. To accomplish this additional advantage I provide the groups of openings E. To cover these openings are provided the lids F. These lids are 105 hinged at the studs A⁷ and normally will occupy the closed positions as shown in Figs. 2 and 3, the openings E being covered and therefore closed. It is desirable that the lids will be normally held to the closed po- 110

sitions so that when the sash bars are being handled in shipment and transporting, the lids will not be in the way, or liable to breakage. Moreover, the lids should be capable of being so secured at closed position that they may not be raised easily by instruments inserted from outside the window. To gain the aforesaid desired advantages is the purpose of my invention shown 10 in detail in Figs. 5, 6 and 7.

On the rods A^8 which are journaled in the lugs A^7 , are secured the lids F . Each of these lids is provided at a central location, with a notch F^1 . Disposed at these 15 notches and held loosely on the rods A^8 are lock dogs G having their body portions G^1 to lie normally on the upper side of the sash bar. The functions of the lugs G^2 will be presently described. Provided at the upper 20 edge of the frontal side of the sash bar is an opening A^9 having a longitudinal offset A^{10} . The rear wall of this offset is slanted slightly as shown in Fig. 8. When the lock dog is at the position as shown in the detail views, 25 the lug G^2 is in tightened engagement with the rear wall of the offset A^{10} , and the main portion G^1 is pressed tightly against the top side of the lid. In turn the lid will be held tightly in engagement with the sash bar. 30 A sash bar so constructed and equipped with the lids F whereby the openings E may be kept either closed or opened, makes it possible to obtain a passing of air currents through the window at intervals of the time 35 and length desired, and without the necessity of moving either of the sashes, and without the necessity of attachments or devices of any kind at the window frame or casement. When the lids are locked in position as shown, the openings E are effectively 40 closed and they will be retained so against effort to open same by instruments from outside the window.

To move the lids to the open position as shown in Fig. 1, the lock dog is grasped at the web G^3 and shifted to the right, the lug

G^2 passing from the offset A^{10} to the opening A^9 . Then by lifting the lock dog the lug G^2 will pass through the opening and the lid may be swung to the open position. 50

What I claim as my invention and desire to secure by Letters Patent, is:—

1. A sash bar having an opening therein, a hinge rod journaled adjacent to said opening, a lid having its edge secured to said hinge rod, there being a recess in the side of said lid at said hinge rod, and a notch being provided in the front side of said sash bar to register with said recess and having an offset therein, a lock dog disposed in said recess and held loosely on the said hinge rod and provided with a lug to engage said offset, the main portion of said dog being adapted to lie normally on the said lid. 60

2. In window construction, a sash bar 65 having an opening therein, a hinge bar journaled adjacent to said opening, a notch in the side of said sash bar and having an offset therein with a beveled seat, a lid having its edge secured to said hinge rod there being a recess in the side of said lid at the hinge rod of length greater than that of the notch, and a lock dog disposed in said recess and held loosely on the hinge rod and provided with a lug to engage said offset. 70

3. In window construction, the combination of a sash bar having an opening therein and a notch at its upper edge provided with an offset, a lid hingedly connected to the sash bar and adapted to cover said opening and having a recess at its hinged side, a longitudinal bar across said recess and in axial alignment with the hinge center, and a lock dog held loosely on said bar and having a lug to engage said offset and its 85 main portion to rest normally on the lid. 80

In testimony whereof I affix my signature in presence of two witnesses.

EMMA M. CLEVENGER.
